Patented Jan. 30, 1973

226,188

SNOWMOBILE

Richard G. Reed, 22656 Nona, Dearborn, Mich. 48124

Filed Jan. 18, 1971, Ser. No. 107,607

Term of patent 14 years

Int. Cl. D12—14

U.S. Cl. D14—24

Fig. 1

Fig. 2

Fig. 3

Fig. 4

FIG. 1 is a side elevational view of the snowmobile showing my new design.

FIG. 2 is a top plan view of the snowmobile shown in FIG. 1.

FIG. 3 is a front view; and

FIG. 4 is a rear view.

The side opposite that shown in FIG. 1 is a mirror image except that the end portion of the exhaust pipe is not seen.

I claim:

The ornamental design for a snowmobile, substantially as shown and described.
